Primary Examiner — Caron D Veynar*Assistant Examiner* — Mehri Bajoul(74) Attorney, Agent, or Firm — Martensen IP(57) CLAIM

The ornamental design for the handheld vaporizer, as shown and described.

DESCRIPTION

FIG. 1 is a front right perspective of the handheld vaporizer.

FIG. 2 is a front view of the handheld vaporizer.

FIG. 3 is a rear elevation view of the handheld vaporizer

FIG. 4 is a right side elevation view of the handheld vaporizer.

FIG. 5 is a left side view of the handheld vaporizer.

FIG. 6 is a top view of the handheld vaporizer; and,

FIG. 7 is a bottom view of the handheld vaporizer.
